UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLURAL LAMP-SOCKET.

No. 898,826.

Specification of Letters Patent.

Patented Sept. 15, 1908.

Application filed March 1, 1907. Serial No. 360,091.

To all whom it may concern:

Be it known that I, REUBEN B. BENJAMIN, a citizen of the United States, residing at Chicago, in the county of Cook and State of Illinois, have invented new and useful Improvements in Plural Lamp-Sockets, of which the following is a full, clear, concise, and exact description, reference being had to the accompanying drawing, forming a part of this specification.

My invention relates to improvements in electric lamp clusters, and particularly to a plural lamp-socket provided with a plug adapted to be inserted into an ordinary 15 socket or receptacle.

One of the objects of the invention is the provision of a device of this type which is made up of but few parts, which is economical to manufacture, and which is, at the 20 same time, efficient and durable.

In the accompanying drawings Figure 1 is a central vertical sectional view of a device embodying my invention; and Fig. 2 is a cross-sectional view of the same, the section 25 being taken on the line 2—2 of Fig. 1, looking in the direction indicated by the arrows.

In these figures, in which like reference numerals indicate the same parts throughout, 5 is a base formed of porcelain or other 30 suitable insulating material. This base 5 is provided with a plug 6, having thereon an outer contact member 7, this outer contact member preferably consisting of a threaded shell adapted to be sleeved onto the plug 6. 35 The opposite side of the base 5 is formed or provided with a projection 8. An opening 9 extends through the base, passing longitudinally through the plug 6 and projection 8. A bolt 10 is inserted into the opening 9, the 40 outer end of this bolt serving as the center contact of the plug. Upon the opposite or inner end of this bolt 10 is a plate 11 secured thereto by a nut 12, the plate 11 serving as a contact member for engaging the center 45 terminals of the lamps.

The plug 6 is provided with other apertures 13 and 14, through each of which extends a bolt 15 and 16. The threaded contact-shell 7 is formed with an inturned flange 50 17 extending around its upper edge and engaged by the heads of the bolts 15 and 16. Upon the inner side of the base 5 are arranged metallic plates 18 and 19, these plates being secured in place by screws 18^a, 19^a,

and further secured by the bolts 15 and 16. 55 The projection 8 on the base is formed with recesses 8^a and 8^b in each of which rests one end of one of the plates 18 and 19, whereby the latter are held in position. When the bolts 15 and 16 are turned to tighten the 60 same, the contact shell 7 and plates 18 and 19 are firmly secured to the base and plug and are electrically connected through the medium of these bolts.

A shell 20, substantially hemispherical in 65 form, and carrying the various lamp-holding devices, is supported upon the plates 18 and 19, this shell 20 being formed with openings in the form of slits 21 and 22 through which project the ends of the plates 18 and 19, the latter being turned up at an angle to their body portion to retain the shell 20 in place thereon. By means of this connection, the shell 20 is sustained and is electrically connected with the outer contact 7 of the plug. 70

The shell 20 is formed with a plurality of openings, in each of which is secured a lamp-contacting member adapted to engage the outer terminal of a lamp. When the device is arranged for lamps of the Edison type 80 these members will consist of threaded sockets 23 for receiving the lamps. When the lamps are inserted into these sockets the center terminal of each of the lamps will engage the plate 11. 85

When it is desired to adapt the device to the use of a lamp disposed in axial alignment with the bolt 10, one of the lamp-sockets will be arranged axially with this bolt, as shown in Fig. 1, and the end of the bolt 10 will serve 90 as the center contact for a lamp.

The outer casing or cover 24, which is of substantially hemispherical form, is provided with suitable openings for the insertion of the lamps, and in each of these openings is arranged a threaded insulating bushing 25 surrounding the sockets 23 and separating them from this cover 24. When these bushings are screwed into place they serve to sustain the cover 24 in place with its edge in engagement with the edge of the base 5 without other means of support.

When this device is provided with lamps, the circuits are through the bolt 10 to the plate 11, thence through the center terminals 105 of the various lamps and the filaments thereof to the outer terminals of these lamps, thence through the sockets 23 to the shell 20,

thence through the plates 18 and 19 to the bolts 15 and 16, thence to the outer contact member 7.

Having thus described my invention, what I claim as new and desire to secure by Letters Patent is:

1. In a plug-cluster, the combination of a base having a plug upon one of its sides and a contact plate upon its opposite side, center 10 and outer contacts upon said plug, electrical connection between said center contact and said plate, a bowl-shaped shell mounted upon said base, a plurality of circularly arranged lamp-holders and an axially disposed lamp- 15 holder carried by said shell, and electrical connection between the outer contact of the plug and said shell.
2. In a plug-cluster, the combination with a base having a plug on one of its sides, of a 20 threaded shell mounted upon the plug to form the outer contact thereof, a plate mounted on the inner side of said base, a center contact upon the plug electrically connected with said plate, a circular shell mounted upon the inner side of said base and having a plurality of openings, one of said openings being in axial alinement with said plug, a threaded lamp-receiving shell in each of 25 said openings, and electrical connection between the outer contact member of the plug 30 and said circular shell.
3. In a plug-cluster, the combination with a plug having a center contact and an outer contact adapted to coöperate with the contacts of a suitable receptacle, of a plurality 35 of lamp-holding devices carried by said plug, one of said lamp-holding devices being disposed in axial alinement with said plug, lamp-terminal-contacting devices associated 40 with said lamp-holding devices, and electrical connection between the contacts of the plug and said contacting devices.
4. In a plug-cluster, the combination with a plug having a center contact and an outer 45 contact adapted to coöperate with the contact of a suitable receptacle, of a lamp-holding device carried by and disposed in axial alinement with said plug, a plurality of cir-

cularly arranged lamp-holding devices carried by said plug, lamp-terminal-contacting 50 devices associated with said lamp-holding devices, and electrical connection between the contacts of said plug and said contacting devices.

5. In a plug-cluster, the combination with 55 a plug having a center contact and an outer contact adapted to coöperate with the contacts of a suitable receptacle, of a circular shell carried by said plug and supporting a plurality of lamp-holding devices, said shell 60 being electrically connected with one of the contacts of the plug, and means for conducting current from the other contact of said plug to the center terminals of all the lamps, one of said lamp-holding devices being disposed in axial alinement with said plug. 65

6. In a plug-cluster, a plug having a threaded shell sleeved thereon to constitute an outer contact for said plug, means carried by said plug providing a center contact for a plurality of lamps, a bowl-shaped member adapted to support a plurality of circularly arranged lamps and an axially disposed lamp and to conduct current to the outer contacts of the lamps, and a bolt extending 75 through said plug and securing said threaded shell to the plug and providing electrical connection between said plug and said bowl-shaped member.

7. In a plug-cluster, the combination of a 80 plug, a bowl-shaped shell carried by said plug for supporting a plurality of lamps, a bolt extending centrally through said plug, and means supported by said bolt for conducting current to the center contacts of a 85 plurality of said lamps, the inner end of said bolt forming the center contact for another of said lamps.

In witness whereof, I have hereunto subscribed my name in the presence of two witnesses.

REUBEN B. BENJAMIN.
